ROTOR FOR ROTARY ENGINES

Eugen Silbermann, Oradeamare, Rumania, assignor to Explorotor A. G., Glarus, Switzerland, a corporation of Switzerland

Application April 16, 1931, Serial No. 530,467
In Switzerland April 22, 1930

5 Claims. (CL 253—32)

This invention relates to rotors for rotary power engines, in which rotors the working path for the driving medium may be formed either by channels provided in the body of the rotor or by spaces between blades carried on the periphery of said rotor, this application being a continuation of my copending applications Serial Nos. 408,199 and 494,405. The first of said applications relates to a rotor in which the channels are enlarged at that side thereof which is foremost with relation to the direction of rotation of the rotor. The second of said applications relates to a rotor in which the channels are shaped to conform to three-dimensional curves. The object of the present invention is to impart to the working path for the driving medium a contour corresponding to the path of flow which the driving medium would naturally take if uninfluenced by any forces other than continuous flow and centrifugal force. More specifically, the object of the invention is to provide a rotor having channels for the passage of the driving medium of such contour that each molecule of the driving medium while passing through the channels will be under the influence of two motions, namely, a progressing motion produced by the delivery of the driving medium into the channels of the rotor, and a rotating motion caused by the rotation of the rotor. The resultant of these motions indicates the direction of the path of flow to which the channels must be suited, which path is a helix of possibly variable pitch and diameter, and will very closely approximate a geodetic line on a surface of rotation the generatrix of which is a curve of the second degree, that is to say, a curved line the osculating plane of which at every point is normal to said surface of rotation. Further objects of the invention will appear as the description proceeds.

40 In the drawing accompanying this specification, Fig. 1 is a central longitudinal sectional view through a conventional form of housing in which is mounted a rotor embodying the features of the present invention;

45 Fig. 2 is a transverse sectional view taken approximately on the line II—II of Fig. 1;

Figs. 3 to 6 inclusive are diagrammatic views illustrating rotors having respectively a cylindrical, an enclosed hyperboloid, a conical and a spherical surface, the dotted lines indicating the center lines of channels formed in the surfaces of said rotors;

50 Fig. 7 is a broken away side view illustrating a rotor in the form of a shaft provided in its periphery with channels extending helically

across the shaft and decreasing in width toward their opposite ends;

5 Fig. 8 is a view similar to Fig. 7 of a shaft-rotor, the channels in this instance having branch ducts;

Fig. 9 is a broken away sectional view illustrating a constructional form of a rotor such as shown diagrammatically in Fig. 3;

10 Fig. 10 is a cross sectional view illustrating a further form of rotor;

Fig. 11 shows in perspective the shape of one of the rotor passages according to Fig. 12;

15 Figs. 12 and 13 show longitudinal sections of two further forms of rotors having distributing chambers co-operating with the passages;

Fig. 14 is a sectional view illustrating a rotor built up of a plurality of plates carrying complementary portions of the channels.

20 Referring to Figs. 1 and 2, there are arranged inside a cylindrical casing 1 a plurality of rotor discs 2, 3, 4 which are fixed on a common shaft 5. A gastight joint between the rotor members and the casing may be effected by any known suitable means provided either on the periphery of the rotor members or at the sides thereof, as 25 by ribs 6 provided on the bore of the casing and engaging the sides of the rotor members as shown applied to the rotor member 4.

25 As heretofore explained, it is desirable that the contour of the channels resemble geodetic 30 lines on surfaces of rotation. It will be observed that in all of the embodiments of the rotors herein suggested, this characteristic is present. The passages 7 may also be provided with lateral 35 branch passages as indicated in Fig. 8 in order to increase the area of the working face.

According to Figs. 3 to 6 each passage 7 encircles the axis of rotation more than once, thus forming an advancing spiral with a constant 40 or variable diameter. The pitch of the spiral may also be nil, so that with a varying diameter it becomes a flat spiral, as indicated in Fig. 9.

With passages thus formed there is a single 45 passage instead of the interrupted wave line path which the driving medium takes in passing through the stator and rotor blades of known multi-stage turbines, so that the rotor discs having passages of this kind also function in the manner of a stator guide, inasmuch as the passage forms successively alternate guide and rotor 50 portions.

Fig. 9 shows diagrammatically a part of an engine in which the driving medium has a spiral travel according to the construction shown in Fig. 3. These passages are formed by grooves 55

in the rotor which is closed by the wall of the fixed housing 57.

The passages may be so shaped that their cross sections remain the same, throughout their length, or the cross section may increase or diminish in the direction of flow. It may also be found desirable to decrease the cross section from the interior of the passage towards both ends, as indicated in Fig. 7.

10 These forms of passages enable the conditions of flow to be varied to suit the nature of the driving medium or the method of driving. Inasmuch as the driving medium passes to the passages in the form of impulses, the explosion taking place immediately before reaching the passages, there is first an impact action followed by a reaction as a result of expansion of the gases. It will depend mainly on the kind of driving medium employed whether the channels are so formed that the flow in the passages is supported by centrifugal force, or is opposed by the latter, or whether the one action takes place in the first part of the passage and the other in the second part, in order to first increase the reaction by back pressure and then rapidly eject the driving medium from the passage.

15 The cross section of the passage is such that it presents surfaces which are more concave than convex relatively to the direction of rotation of the rotor, so that the driving medium is utilized as fully as possible.

20 The cylinder 1 as shown in Fig. 1, has an explosion chamber 8 provided with apertures 9, 10 for the ignition and the introduction of the driving medium, these features being shown conventionally in the drawing. The rows of passages in the rotor members may increase in diameter in the direction of the flow of the driving medium and in accordance with the reduction of pressure, 25 so that all the rotor members exert an equal torque on the shaft. The diameter of the rows of passages may also be equal, while however increasing the total cross sectional area of the passages of the second and following stages by 30 increasing the number of passages or their area. The gases passing from the chamber through the passages in the rotor members exert on the walls of such passages a pressure the direction of which is transverse to the shaft in the case of 35 all the passages, so that the rotor discs are rotated.

40 The driving medium may be benzine or crude oil, or especially ammonium nitrate, chlorates, naphthalene, picrates and so forth, and the engine may be adapted to operate without means for guiding the driving medium to the passages. The driving medium from the explosion chamber acts on all the passages simultaneously, as it enters all of them simultaneously and acts 45 from the centre in all directions. No guide members are required as the distribution is effected by controlling the explosions, i. e. by timing the explosions.

45 The known bladed rotors rotating inside a housing have their efficiency reduced by ejection losses. These losses do not occur in rotors having passages, but there are however rotating surfaces which oppose the driving medium, namely those parts of the inside of the passages which 50 are opposite those acted upon by the driving medium. Experience has shown that a favor-

able efficiency is obtained by a combination of the two systems. According to Figs. 10 and 11, the passages 43 communicate at the inlet end with a slot 44, these slotted ends issuing to the fixed housing 45. Their other ends 46 (the reaction zones) are not slotted. A perspective view of the inner wall of one of the passages 46 is shown in Fig. 11.

55 In the engines above described the gases flow from a hollow chamber disposed in the axis of rotation through the passages, the flow being possibly promoted by centrifugal force. Fig. 12 shows however, an arrangement in which this flow is reversed. The gases are conducted from the suction or explosion chamber 8 to the outer ends of the passages 41 in the rotors 40. These passages lead to a common collecting chamber 42 from which they are discharged. In this case it will be generally advisable to provide passages the cross section of which increases, so that the resistance to the gases in the passages is reduced. Fig. 13 shows an analogous engine having an outside explosion chamber 24 and an annular distributor 22.

25 In order to facilitate the production of the passages, and to enable them to be given a smooth face, the rotor (Fig. 14) may be built up of a number of parts 57 to 60, such parts having each a short length of passage which may be readily machined. When the parts are assembled they present collectively a passage of the desired length, and do not require a stationary distributing guide member.

30 What I claim is:

1. In a rotor for rotary engines in which the propelling medium operates intermittently, channels for the passage of a propelling medium the longitudinal axis of each of which channels follows a continuous three-dimensional curve substantially coincident with a geodetic line on a surface of rotation of the second degree the generatrix of which is a curve of the second degree and conforming to the path of flow taken by the said medium when considered merely as moving forwards with a velocity determined by given running conditions of the engine and at the same time travelling round the middle axis of the rotor with a velocity determined by the given normal speed of the engine.

2. In a rotor for rotary engines channels as claimed in claim 1 each of which describes at least one complete helical turn and is of a cross-sectional area increasing towards that side thereof which is foremost relatively to the direction of rotation of the rotor.

3. In a rotor for rotary engines, channels as claimed in claim 1 disposed on the periphery of the rotor, each of which channels describes at least one complete helical turn and is of a cross-section area increasing towards that side thereof which is foremost relatively to the direction of rotation of the rotor.

4. In a rotor for rotary engines, channels as claimed in claim 1 having lateral branch passages the walls of which are adapted to form surfaces of reaction with respect to the said propelling medium.

5. In a rotor for rotary engines, channels as claimed in claim 1 of diminishing cross-sectional area towards both ends thereof.

EUGEN SILBERMANN.
